UNITED STATES PATENT OFFICE

2,063,053

RESPIRATOR

Daniel H. Roche, Kansas City, Mo.

Application February 11, 1933, Serial No. 656,339

7 Claims. (Cl. 128—148)

My present invention relates to new and useful improvements in a respirator and in so far as there is common subject matter the present application is a continuation in part of my applications filed September 22, 1927, Serial No. 221,316 (Patent No. 1,802,275, dated April 21, 1931) and July 8, 1929, Serial No. 376,700.

The principal object of the invention resides in the provision of a member which may be readily positioned on the nose or removed therefrom and a separate member adapted to be positioned over the mouth and connected to the member which is positioned on the nose.

Another object of the invention resides in the provision of a member which may be readily positioned on the nose or removed therefrom, wings being provided for swinging movement so that they may be properly positioned over the openings of the nose or left spaced therefrom and such wings carrying gauze or other suitable material through which the air drawn into the nostril may be filtered.

A further object of the invention consists in the provision of a member adapted to be positioned over the mouth including a frame adapted to carry gauze or other suitable filtering material and means whereby the member may be held in proper position over the mouth, said means including a loop adapted to be engaged with a member positioned on the nose.

Still another object of the invention consists in the provision of a member adapted to be connected to the nose, said member including a frame adapted to be connected to the nose partition and having a depending central portion, members adapted to be engaged with the walls of the nose, and wings adapted to be adjusted relative to the nose openings.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:

Fig. 1 is a front view showing the nose member of the respirator in position attached to the nose.

Fig. 2 is a fragmental detail showing a section through the frame which is engaged with the nose partition with associated parts shown in side elevation.

Fig. 3 is a detail showing a side elevation of one of the wings with the filtering material positioned thereon.

Fig. 4 is a horizontal section through the gauze forming pockets for the wings with the wings shown in top plan.

Fig. 5 shows a top plan of one of the wings and a horizontal section through the fabric pocket, the pocket being provided with an extension.

Fig. 6 is a side elevation showing the face of the wearer with the respirator including the nose member and mouth member in position.

Fig. 7 is a front elevation, with parts broken away, of the member adapted to be positioned over the mouth.

Fig. 8 is a vertical section through the mouth attachment.

Fig. 9 is a fragmental detail showing the manner of connecting the mouth attachment to the nose attachment; and

Fig. 10 is a fragmental detail showing one of the connecting members for the elastic bands used in positioning the mouth attachment on the face of the wearer.

In the drawings *a* indicates the member adapted to be positioned on the nose and *b* indicates the member adapted to be positioned over the mouth. Referring to the member *a* *1* indicates a substantially U-shaped frame preferably formed from a strip of resilient metal which may be bent into the desired shape or more particularly into the shape illustrated in Fig. 1 of the drawings with a depending central portion *2* providing a finger grip to be engaged for positioning the member relative to the nose and permitting adjustment or widening of the frame when desired to adapt the same for partitions of different thicknesses.

The ends of the strip forming the frame are made to provide the substantially vertically extending eye portions *3* which depend from the frame, and intermediate the ends of the frame the strip is made to form the inwardly extending arms *4* having the substantially horizontally extending eyes *5* formed at the inner ends thereof. As quite clearly shown in Fig. 1 of the drawings the inner ends of the arms *4*, at the points of the eyes *5*, are spaced a distance apart so as to receive the partition wall *6* of the nose therebetween. The frame is preferably resilient so that it may be sprung sufficiently to allow the partition wall of the nose to pass between the inner ends of the arms and when released the arms will engage on opposite sides of the partition wall as shown. As previously stated the depending portion *2* permits the frame to be adjusted or widened at will.

Extending through the eyes *5* of the arms *4*, and frictionally held therein, are the rods *7* having their inner ends bent to form the arms *8* and the extensions *9*. The arms, as quite clearly shown in Fig. 1 of the drawings, extend outwardly in opposite directions to engage the inner surfaces of the outer walls of the nose. The extensions *9* are adapted to engage the lip *10* just below the

nose as shown more particularly in Fig. 2 to aid in holding the device in position on the nose.

Mounted on the rods 7, and frictionally held thereon, are the sleeves or tubes 11 which are positioned between the extensions 9 and the ends of the eyes 5, these sleeves or tubes being adjustable on the rods to position the rods or extensions 8 to properly position and hold the frame 1 on the nose partition, it being understood that the ends 10 of the tubes or sleeves will engage the ends of the eyes 5.

Extending through the depending substantially vertically extending eyes 3 are the rods 12, said rods being of such a diameter as to snugly fit the interior of the eyes and adapted to be held by friction. The lower ends of the rods are bent in the manner shown to form the portions 13 and 14 with the diagonally extending arms 15 formed on the ends of the portions 14. The arms 15 will receive the wings to be later described and particular attention is directed to the fact that the rods 12 are rotatably mounted in the eyes but are held against sliding movement by means of the inturned extensions 16 formed on the lower ends 25 of the eyes 3, as shown more particularly in Fig. 2 of the drawings. The extensions 16, as shown, engage beneath the portions 13. The rods 12 being rotatable in the eyes permit adjustment of the rods 15 to properly position the wings carried thereby, beneath the openings of the nose.

The wings which are both slidably and rotatably mounted on the arms 15 consist of frame portions which are covered by gauze or other similar material. The construction of the frame portions of the wings is quite clearly illustrated in Fig. 3 of the drawings and each of the frames consists of the three sections indicated at 17, 18 and 19, the sections being connected together for sliding adjustment whereby the size of the frame may be 40 adjusted as desired. The section 17 is formed at the outer end with an eye 20 through which the arm 15 is adapted to extend. This eye is of such a diameter as to snugly fit the arm 15 so that there will be sufficient friction to hold the wing in its adjusted positions relative to the arm. The section 18 is provided at each end with the in-turned flanges 21 forming guides for the ends of the sections 17 and 19, as shown more particularly in Fig. 3 of the drawings and the section 19 includes an arm 22 which extends parallel with the section 17. Each of the sections 18 is provided on one face with an outwardly extending pin 23 and each of the sections 19 at the juncture with its arm 22 is provided with a similar pin 24, these pins being used for purposes to be later described. A pocket of gauze or similar material is adapted to receive each of the frames and to form a part of the adjustable wings as shown in the drawings, one of the pockets of gauze being shown at 25 and the other at 26, the pocket 25 having the extension 27 for a purpose to be later described. The pins 23 and 24 will engage and extend through the gauze pockets and thereby hold the same upon the frames and when the frames are swung as shown in Figs. 1 and 4 into the position over the nose openings the extension 27 will be engaged with the pins 23 and 24 on the opposite frame and extend over the space between the adjacent edges of the two frames. Each of the wings is provided, at the end of the arm 22, with a hook or projection 28 for a purpose to be later described and when the wings are swung to cover the nose openings the hooks or projections will be in close proximity as they are on adjacent portions of the wings.

From the above detailed description of the member to be attached to the nose it is thought that the construction and manner of using will be readily understood. The member is adapted to be attached to the nose and the wings carrying the gauze or other filtering material are adapted to be swung into position over the nose openings as shown more particularly in Fig. 1 of the drawings. When applying the member the depending portion 2 will be grasped for positioning the frame 1 upon the nose partition 6, as shown more particularly in Fig. 1 of the drawings and the arms 8 will be positioned so that their ends engage the inner faces of the walls of the nose while the extensions 9 will engage the lip 10 of the wearer just below the nose as shown more particularly in Fig. 2. As previously stated if it is desired to widen the frame 1 this can be done by springing the ends of the arms 4 apart, the depending portion 2 permitting this adjustment. With the frame thus attached to the nose the wings will be adjusted so that the filtering material forming a part thereof will extend beneath and cover the nose openings. The rods 12 are rotatably mounted in the sleeves 3, as previously stated, and the wings or frames are adjustable on the arms 15 for either rotatable or slidable movement. The arms 15 will extend through the gauze covering the frames or wings when entering the sleeves or eyes 20. The rods 12 are held against any sliding movement within the sleeves or eyes 3 by means of the inturned extension 16 as shown more particularly in Fig. 2 of the drawings. In removing the device from the nose the extensions 9 will be grasped and manipulated to rotate the rods 7 in the eyes 5 so as to swing the ends of the arms 8 from engagement with the walls of the nose and in position to be withdrawn from the nose openings. In applying the device the extensions 9 will be engaged and moved in the opposite direction to engage the ends of the arms with the walls of the nose.

The member adapted to be positioned over the mouth is shown more particularly in Figs. 6, 7, 8, 9 and 10 of the drawings and includes the frame 29 and gauze covering 30, this covering 30 acting as the filtering material. Secured to opposite ends of the frame are the resilient or expandible metal loops or sleeves 31 in each of which is adjustably positioned an elastic band 32, the bands being held within the sleeves or loops by friction but adapting the same to be adjusted therein. Each of these loops or sleeves 31 has a hook portion 31' engaged through the fabric and with the ends of the frame. Secured to the outer end of each of the bands 32 is a connecting member or guide including the resilient sleeve 33 and eye 33', the eye being positioned at right angles to the sleeve 33. The elastic bands 32 are held in the sleeves 33 by friction and extending through the eyes 33' are the opposite ends of an elastic band 34, the ends of the bands being held within the eyes by friction but adapted for adjustment therethrough. The ends of the band 34 are connected by means of a resilient sleeve or clip 35 shown more particularly in Fig. 6 of the drawings, and as shown also in this figure when the mouth attachment is in position the band 34 will extend around the head 70 of the wearer whereas the connected ends of the band form a loop portion indicated at 36 which is adapted to extend beneath the chin. It will thus be seen that the bands 32 as well as the band 34 are adapted for adjustment to permit the at- 75

tachment to be worn by persons with different size heads. Secured to the upper edge of the fabric 30, intermediate the ends thereof, is a loop 31 which is adapted to be engaged with the hooks or extensions 28, on the nose member whereby the mouth attachment may be connected to the nose member and held in proper position relative thereto. Carried by the band 34 are the sleeves or stops 38, which are adapted to engage the eyes 33', as shown more particularly in Fig. 7 of the drawings, to properly position, after adjustment, the ends of the band 34 relative to the bands 32.

A respirator such as I have described and illustrated is of particular advantage in preventing the entrance of impurities into the nose or mouth and may be worn by travelers in trains or motor vehicles, by engineers or firemen, by those who suffer from hay fever or the like to prevent pollen from entering the nose or mouth, or in fact, by anyone who desires to prevent the entrance of dust or other impurities into the nose or mouth. By having the several parts adjustable, as has been described, the device is adapted for use under varying conditions and the filtering material may be changed when desired.

Having fully described my invention what I claim as new and desire to secure by Letters Patent is:—

30 1. In a respirator, a member adapted to be connected to the nose, said member including a resilient frame having a portion adapted to be engaged with the nose partition and formed with substantially horizontally extending eyes and substantially vertically extending eyes, arms carried by the substantially horizontally extending eyes and adapted to be engaged with the side walls of the nose and with the lip of the wearer, said arms being slidably and rotatably mounted 40 in the eyes and frictionally held therein, rods rotatably mounted in the vertically extending eyes, extensions on the vertically extending eyes and engageable with said rods for preventing sliding movement thereof and filtering members 45 carried by the rods.

2. In a respirator, a member adapted to be connected to the nose, said member including a resilient frame having a portion adapted to be engaged with the nose partition and formed with substantially horizontally extending eyes and substantially vertically extending eyes, the vertically extending eyes depending from the frame, arms carried by the substantially horizontally extending eyes and adapted to be engaged with the side walls of the nose and with the lip of the wearer, said arms being slidably and rotatably mounted in the eyes and frictionally held therein, rods rotatably mounted in the vertically extending eyes, extensions on the vertically extending eyes and engageable with said rods for preventing sliding movement thereof, and filtering members carried by the rods.

3. In a respirator, a substantially U-shaped member of resilient material adapted to be engaged with the partition of the nose and formed with substantially horizontally extending eyes at the upper ends of the limbs, a pair of arms each having a substantially straight horizontal part, a depending substantially U-shaped part, the limbs of which are substantially straight and vertically arranged, the outer limb being extended above the straight horizontal part and curving outwardly for engaging portions of the

internal walls of the nostril, the lower portion of said limb engaging a portion of the lip, a portion of the horizontal part being slidably and rotatably mounted in an eye and held in an adjusted position by friction. 5

4. In a respirator, a substantially U-shaped member of resilient material adapted to be engaged with the partition of the nose and formed with substantially horizontally extending eyes at the upper ends of the limbs, a pair of arms 10 each having a substantially straight horizontal part, a depending substantially U-shaped part, the limbs of which are substantially straight and vertically arranged, the outer limb being extended above the straight horizontal part and curving outwardly for engaging portions of the internal walls of the nostrils, the lower portion of said limb engaging a portion of the lip, a portion of the horizontal part being slidably and rotatably mounted in an eye and held in an 15 adjusted position by friction, and a sleeve slidably arranged on the horizontal part and held in adjusted position by friction, said sleeve being considerably shorter than that part of the horizontal portion which extends between the 20 eye and the inner limb of the U-shaped part of the arm, said sleeve engaging the eye and acting as an adjustable stop for limiting movement of the arm through the eye. 25

5. In a respirator, a frame adapted to engage 30 the nose partition and formed with substantially horizontally extending eyes at its upper portions, rods rotatably and slidably mounted in said eyes and having portions adapted to engage the nose and lip of a user, said eyes normally holding the rods in position by friction, tubular stops snugly and slidably disposed on the rods for engagement by the eyes to position the rods in case the said eyes have to be loosened to permit the rods to revolve freely. 40

6. A nose frame or respirator including a frame adapted to be engaged with the nose partition, rods carried by the frame, and filtering members carried by the rods and adjustable relative to the nose, each of said filtering members consisting of a sectional frame, the sections being connected for sliding adjustment and frictionally held whereby the frame can be adjusted to the required size to accommodate filtering material of any required size, and one section having a sleeve to receive the rod which carries the member, casings of filtering material for entirely inclosing the sectional frames, one casing for one sectional frame having an extension on one side to overlap and fasten on the other sectional frame, for closing the space between the two sectional frames, said sectional frames having pins for engaging the material to hold the same in position. 50 55

7. In a respirator of the class described, a substantially U-shaped member having the upper portions of the limbs bowed outwardly, the extremities of the limbs being adapted to be engaged with the nose partition, said member being formed of resilient material, whereby by 65 bending the lower part of the member the space between the extremities can be adjusted to fit different sizes of nose partitions and depending finger gripping portions connected with the extremities and extending below the bight of the 70 U-shaped member.

DANIEL H. ROCHE.
